UNITED STATES PATENT OFFICE

132,628

DESIGN FOR A COVER-PLATE FOR A SEWING MACHINE

Malcolm S. Park, Mount Kisco, N. Y., assignor
to The Singer Manufacturing Company, Eliza-
beth, N. J., a corporation of New Jersey

Application April 18, 1942, Serial No. 106,618

Term of patent 14 years

To all whom it may concern:

Be it known that I, Malcolm S. Park, a citizen
of the United States, residing at Mount Kisco,
in the county of Westchester and State of New
York, have invented a new, original, and orna-
mental Design for a Cover-Plate for a Sewing
Machine, of which the following is a specifica-
tion, reference being had to the accompanying
drawing, forming a part thereof.

Fig. 1 is a top perspective view of a cover plate
for a sewing machine showing my new design.

Fig. 2 is a bottom perspective view of the
sewing machine cover plate shown in Fig. 1.

I claim:

The ornamental design for a cover-plate for a
sewing machine, as shown.
